PICTURE FRAME OR SIMILAR ARTICLE

Ida Pedersen, Chicago, Ill.

Application October 23, 1957, Serial No. 48,218

Term of patent 14 years

(Cl. D29—20)

Fig. 1 is a perspective view of a picture frame or similar article embodying my new design; and

Fig. 2 is a reduced perspective view thereof with the inner element and a portion of the outer frame in disassembled position.

The sides not shown are substantially the same in appearance as the sides shown.

The dominant features of my design reside in the portion shown in full lines.

I claim:

The ornamental design for a picture frame or similar article, substantially as shown and described.
